Patented June 10, 1924.

1,496,833

UNITED STATES PATENT OFFICE.

EARL C. SHERRARD, OF MADISON, WISCONSIN. DEDICATED, BY MESNE ASSIGNMENTS,
TO THE PEOPLE OF THE UNITED STATES OF AMERICA.

STOCK FOOD AND PROCESS OF MAKING SAME.

No. Drawing.

Application filed November 27, 1922. Serial No. 603,690.

(FILED UNDER THE ACT OF MARCH 3, 1883, 22 STAT. L., 625.)

To all whom it may concern:

Be it known that I, EARL C. SHERRARD, a citizen of the United States of America, and an employee of the Department of Agriculture, residing in Madison, Wisconsin, whose post-office address is Department of Agriculture, Madison, Wisconsin, have invented a certain new and useful Stock Food and Process of Making Same, of which the following is a specification.

This application is made under the act of March 3, 1883, Chapter 143 (22 Stat., 625), and the invention herein described and claimed may be used by the Government of the United States or any of its officers or employees in the prosecution of work for the Government and also by any person in the United States, either in public or private work, without payment to me of any royalty thereon.

My invention consists in subjecting sawdust, finely comminuted wood waste or other cellulose containing material to the action of a dilute acid under pressure for varying periods of time. This treatment causes a portion of the wood to hydrolyze with a production of about 18 to 25 per cent sugar. After leaching the sugar from the digested dust with hot water, neutralizing the acid with a suitable reagent such as lime, calcium, carbonate, soda, ash, etc., the settled or filtered liquor is evaporated. The heavy syrup obtained by evaporation of the sugar solution is then mixed with the partially dried extracted dust and the whole evaporated to about eight to fifteen per cent moisture. The product produced in this way is comparable to a grain and may be used as such in a standard ration.

The process of manufacturing this material in more detail is as follows:

The wood in the form of sawdust or finely shredded slabs and edgings is placed in a digester, preferably a rotating digester, together with sufficient water to make the ratio of water to wood about 1:1 or 2.5:1 after the digestion is complete. The acid is introduced at the same time with the water in quantities corresponding to 0.5 to 2.5% of the dry weight of the wood. The per cent of acid required will vary somewhat according to the time of cooking and the steam pressure used. The digester is then closed

and steam admitted until the pressure has reached 100-120 pounds for 10 to 20 minutes as noted below. The pressure may be varied according to the time of cooking or to the concentration of acid used. For a standard cook of 10 to 20 minutes with 1.8 per cent acid the steam pressure should be about 120 pounds. The maximum pressure should be reached as rapidly as possible after admitting the steam.

When the digestion is complete the digester is quickly connected to a blow off pipe leading to a condenser or to the open air, and the pressure relieved. By condensing the blow off, considerable quantities of volatile oil can be recovered from coniferous woods. The digested wood is then removed from the digester and the sugars extracted with water in leaching towers, diffusion battery or other extraction apparatus. The quantity of water used will depend upon the nature of the wood and its state of comminution. As a general rule a quantity of water equivalent to three or four times the original weight of the wood is sufficient to remove the greater part of the acid used as the hydrolyzing agent. The solution thus obtained is then neutralized with a suitable neutralizing agent until the liquor shows an acidity of four to five degrees (Am). This neutralization removes not only the greater part of the acid introduced as the catalytic agent but also the greater part of the organic acid such as acetic and formic acids formed during the digestion. This extraction and subsequent neutralization of the acids is considered an important and vital step in the process.

After the partially neutralized solution has been allowed to settle or, if necessary, filtered, the clear liquor is evaporated preferably under reduced pressure, to a thick molasses. This molasses is then added to the extracted dust which may, or may not have been previously pressed or partially dried or both. After mixing the material is placed in an oven or continuous dryer and the moisture content reduced to 8 to 15 per cent.

The concentration of the acid used as the hydrolyzing agent is varied according to the pressure or to the period of time of cooking. For example, a quantity of acid corresponding to 1.8 per cent of the dry weight of the

wood should be used for cooking periods of from 10 to 20 minutes, while for shorter periods the acid strength should be increased. In the same way when longer periods are required, the concentration of acid may be materially lowered in order to avoid a decomposition of the sugars, a reaction that occurs when the acidity pressure or time of cooking is increased.

10 In the same way the quantity of water used should be varied according to the time of cooking. For periods of from 15 to 20 minutes or less and at a steam pressure of 115 to 120 pounds the ratio of water to dry wood should be 1.25 to 1 inclusive of the moisture originally contained in the wood. For longer periods the quantity of water should be reduced in order to compensate for the condensation of steam.

20 The pressure used for cooking the material is dependent upon the concentration of acid used and upon the length of the cooking period. As noted above for a concentration of acid corresponding to 1.8 per cent of the dry weight of the wood and a cooking period of 10 to 20 minutes a pressure of 115 to 120 pounds would be most desirable. For longer digestion periods and greater concentrations of acid the pressure should 30 be somewhat reduced while for shorter periods and lower concentrations of acid it should be slightly increased.

In the same way the time of cooking is dependent upon the concentration of acid and upon the pressure. While the standard cook mentioned above produces the largest quantity of total reducing sugars a longer period produces a slightly greater per cent of the hexose sugars and at the same time 40 decomposes a part of the pentoses with a production of formic and acetic acid. Although the hexoses have a greater food value it is problematical whether the increased yield compensates for the great expense involved in the longer cooking period.

45 The evaporation of the sugar solution should be carried out under reduced pressure and at a temperature not greater than 95 degrees centigrade. It has been found 50 that the sugar content of the final product gradually decreases upon standing if the moisture content is in excess of 15 per cent. For this reason it is essential that the product be dried to about eight to fifteen per 55 cent moisture. The drying should be carried out in an oven or continuous dryer at a temperature of 70 to 90 degrees to avoid decomposition of the sugars. The material is very easily dried and after being dried 60 to eight or fifteen per cent moisture it keeps indefinitely. The moisture content should in no case exceed 15 per cent; otherwise it would spoil on standing.

It has also been found desirable to remove 65 the larger pieces of bark and undigested

wood. This can be done either by screening before digestion or after the extraction of the sugar and acid. It has been found that the moist extracted dust is more easily screened than the original dust and it is 70 thought that the increased ease of operation more than outweighs the increased cost of handling the screenings during digestion and extraction. The loss of material upon screening the extracted dust amounts to 75 about five per cent of the total material placed on the screen.

I prepared a stock food from eastern white pine in accordance with the process described above and it was found to be 80 characterized by containing cellulose which differs from that in the original material in being almost wholly soluble or capable of forming a colloidal solution in a 17 per cent solution of sodium hydroxide and containing 85 practically the same quantity of ligneous material as the original wood.

I claim:

1. A process for preparing a stock food from cellulose containing material which 90 consists in subjecting said material to a digestion for 10 to 20 minutes at a steam pressure of 100 to 120 pounds in the presence of a quantity of acid equivalent to 0.5 per cent to 2.5 per cent of the dry weight of the 95 original material, then extracting the mass with hot water, partially neutralizing the acids in the solution so obtained with a neutralizing agent, such as lime, settling to 100 remove insoluble material, decanting, and, after evaporation to a thick syrup, mixing the syrup with the solid extracted residue from which part of the moisture has been removed.

2. A process for preparing a stock food 105 from cellulose containing material which consists in subjecting said material to a digestion for 10 to 20 minutes at a steam pressure of 100 to 120 pounds in the presence of a quantity of acid equivalent to 0.5 per cent to 2.5 per cent of the dry weight of the 110 original material and in the presence of sufficient water to make the ratio of water to dry material from 1:1 to 2.5:1 after 115 digestion is complete, then extracting the mass with hot water, partially neutralizing the acids in the solution with a neutralizing agent, such as lime, settling to remove 120 insoluble material, decanting, and, after evaporation to a thick syrup, mixing the syrup with the solid extracted residue from which part of the moisture has been removed.

3. A process for preparing a stock food 125 from cellulose containing material which consists in subjecting said material to a digestion for 10 to 20 minutes at a steam pressure of 100 to 120 pounds in the presence of a quantity of acid equivalent to 0.5 per cent to 2.5 per cent of the dry weight of the 130 original material and in the presence of

sufficient water to make the ratio of water to dry material from 1:1 to 2.5:1 after digestion is complete, then extracting the mass with hot water, partially neutralizing the acids in the solution with a neutralizing agent, such as lime, settling to remove insoluble material, decanting, and, after evaporation to a thick syrup, mixing the syrup with the solid extracted residue from which

a part of the water has been removed, and 10 subsequently drying the whole to a moisture content of 8 to 15 per cent.

In testimony whereof, I affix my signature in the presence of two subscribing witnesses.

EARL C. SHERRARD.
